United States Patent Office.

M. C. LEONARD, OF WASHINGTON, DISTRICT OF COLUMBIA.

Letters Patent No. 61,345, dated January 22, 1867.

IMPROVEMENT IN CARTRIDGE BOXES.

The Schedule referred to in these Letters Patent and making part of the same.

TO ALL WHOM IT MAY CONCERN:

Be it known that I, M. C. LEONARD, of the city and county of Washington, in the District of Columbia, have invented a new and improved Cartridge Box; and I do hereby declare that the following is a full and exact description thereof, reference being had to the accompanying drawings, and to the letters of reference marked thereon, forming part of this specification, and in which like parts are represented by like letters in the several figures.

The nature of my invention consists in adapting the ordinary cartridge box to the use of metallic fulminate cartridges, or making new ones in like manner, by simply lining the principal pocket (usually containing tin frames) with sheep skin, having the wool on it, or equivalent elastic cushioned material, which will avoid any explosion of said cartridges by the ordinary carriage.

To enable those skilled in the art to make and use my invention, I will proceed to describe its construction and operation. In the drawings—

Figure 1 represents an ordinary cartridge box, lid raised, the usual tin or metal inner boxes or frames removed, and the entire pocket lined with sheep skin, wool, or other equivalent material.

Figure 2 shows the box, having the rear half removed.

The cartridge box shown is one of the ordinary kind used in the United States infantry, having the tin boxes in which the paper cartridges are packed, removed, and the pocket entirely lined with sheep skin, thus utilizing the box for the fulminate metallic cartridge, fast superseding the other, as the breech-loader takes the place of the old muzzle-loading musket. This lining is marked A. After well-tested experiments, made at the wish of the United States Ordnance department, I found nothing would prevent an accidental explosion of the fulminate cartridge but lining the pocket of the box, as shown and described.

Having thus described my invention, what I claim as new, and desire to secure by Letters Patent of the United States, is—

As a new article of manufacture a cartridge box lined with sheep skin or other equivalent material, and for the purpose set forth.
